UNITED STATES PATENT OFFICE.

ALBERT SPEIRS, OF ATLANTIC HIGHLANDS, NEW JERSEY, ASSIGNOR TO
ALBERT SPEIRS MANUFACTURING COMPANY, OF NEW YORK, N. Y.,
A CORPORATION OF NEW YORK.

PACKAGE FOR PIPE-CLEANERS.

No. 827,045.

Specification of Letters Patent.

Patented July 24, 1906.

Application filed September 27, 1905. Serial No. 280,387.

To all whom it may concern:

Be it known that I, ALBERT SPEIRS, a citizen of the United States, residing at Atlantic Highlands, in the county of Monmouth and State of New Jersey, have invented a new and useful Package for Pipe - Cleaners, of which the following is a specification.

As now placed upon the market the chenille pipe-cleaners are put up in bulk and sold in loose quantities to purchasers, it being customary to place the loose pipe-cleaners in a bag or envelop for convenience in carrying the same. While it is possible to carry several loose pipe-cleaners in a pocket of the clothing, they soon become bent to such an extent as to render them useless for cleaning pipes, and therefore it has heretofore been practically impossible for a smoker to carry with him a supply of pipe-cleaners.

Having appreciated the foregoing disadvantages, I propose to overcome the same, and in this connection to provide for placing pipe-cleaners upon the market in an improved package for containing a predetermined number of pipe-cleaners—say, for instance, one dozen—in such condition that the pipe-cleaners will be maintained in their proper straight condition even when the package is carried in a pocket of the clothing.

It is also proposed to enable the convenient removal of any of the pipe-cleaners whenever desired without any opening or loosening of the package and also to enable the return of a used cleaner to the package without soiling or disturbing any of the other unused cleaners.

A still further object of the invention is to have the package operate as an advertising medium and to arrange for employing certain of the pipe-cleaners in the capacity of legs or brackets for supporting the package in an upright position, so as to fully display the advertising matter which is printed or otherwise provided upon the body of the package.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without

departing from the spirit or sacrificing any of the advantages of the invention.

55

In the drawings, Figure 1 is a perspective view of the package of the present invention supported in a displayed position by two of the pipe-cleaners. Fig. 2 is an elevation of the package with portions thereof broken away to disclose the arrangement of the pipe-cleaners within the cells or compartments of the package. Fig. 3 is an enlarged transverse fragmentary sectional view.

Like characters of reference designate corresponding parts in all of the figures of the drawings.

The present package is in the nature of a flat open-ended rectangular box 1, preferably of such proportions as to conveniently fit 7c within a vest-pocket, so as to enable the carrying of the package about the person. Within this box is a longitudinally-disposed corrugated partition 2, which extends from end to end and from edge to edge of the box 75 or package, with the convexed sides of its corrugations pasted or otherwise secured to the respective front and rear sides of the package, thereby providing the latter with a series of longitudinal cells or compartments 80 which are open at their opposite ends.

The front and back of the package may be provided with any suitable or preferred advertising matter—such, for instance, as indicated in Fig. 1 of the drawings—it being 85 proposed to have such advertising include the price of the package and its contents.

Within each cell or compartment there is an ordinary chenille pipe-cleaner 3, made up of a wire core sheathed or covered with chenille or the like. Each pipe - cleaner is doubled upon itself midway of its ends and thrust endwise into one of the compartments, the latter being of a length to entirely house the pipe-cleaner, so as to prevent bending of the latter by handling of the package and also when the package is carried in a pocket. It is preferred to have the bends of the cleaners lie at one end only of the package and also to project slightly beyond the 100 same, as clearly shown in Fig. 2 of the drawings, so as to afford a sufficient finger-grasp to enable the convenient withdrawal of any individual pipe-cleaner from the package. It will of course be understood that each pipe-cleaner fits with sufficient snugness within its 105

cell or compartment as to prevent the cleaner from working endwise out of the package. By bending each pipe-cleaner at its middle the length of the package for containing the bent cleaners is of a size to be conveniently carried in an upper vest-pocket, and the tendency of the bent cleaners to spread within their cells or compartments produces sufficient frictional engagement between the cleaners and the walls of the compartments as to prevent endwise displacement of the cleaners.

For the purpose of displaying the advertising matter carried by the package—for instance, in show-windows, show-cases, upon counters and the like—each of the terminal cleaners may be drawn outwardly at their free ends and then spread beyond the front and back of the package, as indicated at 4 in Fig. 1 of the drawings, so as to form legs or brackets for the support of the package in an upright position, so as to display the advertising matter carried thereby. The employment of certain of the pipe-cleaners as supports for the package does not in any manner impair the usefulness of the package and the cleaners, as the latter may be pushed back into the package without any injurious effect thereon. It will here be explained that it is proposed to put up a predetermined number of pipe-cleaners—say one dozen—in each package and to place the packages containing the pipe-cleaners upon the market in this condition, whereby the purchaser of one of the packages may place the same in his vest-pocket and carry the same with him at all times in order that he may have a pipe-cleaner at hand whenever required.

From the foregoing description it will be understood that the present device is a combined package and advertising medium and is equipped with pairs of leg members which are normally housed within the package when the latter is in storage and transportation and are capable of being drawn out to support the package in position for displaying the advertising matter contained thereon.

Having thus described the invention, what is claimed is—

1. A combined package and advertising medium comprising a container having a plurality of open-ended longitudinal compartments, and a plurality of pliable pipe-cleaners snugly and removably fitted in the respective compartments and terminally accessible for withdrawal from the container, certain of the cleaners capable of being partially withdrawn from the container to form legs for supporting the body in a displayed position. 50

2. A combined package and advertising medium comprising a flat rectangular box open at opposite ends and provided with a longitudinal partition which is longitudinally corrugated and defines a series of longitudinal open-ended compartments, and a plurality of pliable pipe-cleaners, each cleaner being folded and thrust into one of the compartments with its open end accessible for convenience in withdrawing the same, certain of the cleaners capable of having their free ends projected beyond one end of the box and spread to form supporting-legs for the box. 60 65

3. A combined package and advertising medium comprising a container provided with advertising matter and divided into a series of longitudinal compartments which are open at opposite ends, and a plurality of chenille pipe-cleaners, each pipe-cleaner being folded substantially midway of its ends 70 and thrust into one of the compartments with its bent end accessible for convenience in withdrawing the same, certain of the cleaners capable of having their free ends projected beyond one end of the container and 75 spread toward the front and back of the latter to form supporting-legs for the container. 80 85

In testimony that I claim the foregoing as my own I have hereto affixed my signature in the presence of two witnesses.

ALBERT SPEIRS.
